UNITED STATES PATENT OFFICE.

EDWARD N. LORSCHIEDER, OF NEW YORK, N. Y., ASSIGNEE TO THE LORSCHIEDER-SCHANG COMPANY, OF NEW YORK, N. Y., A CORPORATION OF NEW YORK.

TOILET-CASE.

1,230,912.

Specification of Letters Patent. Patented June 26, 1917.

Application filed May 20, 1915. Serial No. 29,409.

To all whom it may concern:

Be it known that I, EDWARD N. LORSCHIEDER, of New York, in the county of New York and State of New York, have invented certain new and useful Improvements in Toilet-Cases; and I do hereby declare the following to be full, clear, and exact description of the same, reference being had to the accompanying drawings, forming a part of this specification, and to the reference-numerals marked thereon.

My invention has for its object to improve the construction of toilet cases or what are known as vanity cases of the class embodying a receptacle for face powder and the like in conjunction with a mirror carried thereby. More specifically, the invention has for its purpose to provide a very simple arrangement that can be manufactured at low cost, placing the device within reach as a useful, inexpensive novelty. Still a further object of the invention resides in providing a novel organization of parts whereby the addition of a mirror does not add to the cost of the construction, or decrease the volume of the receptacle, which is necessarily small since the purpose requires that the exterior size be reduced as much as possible. To these and other ends the invention consists in certain improvements and combinations of parts, all as will be hereinafter more fully described, the novel features being pointed out in the claim at the end of the specification.

In the drawings:

Figure 1 is a perspective view showing a box embodying my improvement, the closure being open, and

Fig. 2 is a sectional view with the closure shut.

Similar reference numerals throughout the several figures indicate the same parts.

The present embodiment shows the application of the invention to a toilet case or container, more commonly known as a vanity case, made of cardboard or similar material, and comprising a bottom 1, side walls 2, and rear and front walls 3 and 4 respectively.

In order to provide a mirror readily accessible in connection with a case of this character, it is usual to secure a reflecting element, to the inner surface of the closure, but this has the objection that it is likely to become detached, is to a certain extent unsightly, and occupies a portion of the in-

terior when the cover is closed, thus reducing the volume of the container. I prefer to accomplish this by constructing the closure itself of a reflecting material, preferably glass, as designated in the present structure at 5, and it may be silvered or otherwise prepared to afford a mirror on its inner face as designated at 6. The closure may be secured in any desirable manner to the body portion of the case to retain the contents of the latter and I prefer to employ a hinged connection between the body portion and closure in the following manner.

7 designates a covering consisting of cloth or other suitable material which is attached to the body portion of the case and extends around the closure, covering both surfaces thereof and cut away on the under side to form an opening 8 within which is arranged the reflecting portion 6 already mentioned. Thus the covering 7 serves to connect the closure to the body portion, affording a hinged relation between it and the closure and also constitutes an ornamental and protective outer surface. The closure also includes a flap or attaching portion 9 which is connected to the section 5 by means of the covering 7 and is provided with a spring socket 10 co-operating with a fastening device 11 secured to the front wall of the body portion.

My invention is designed more particularly with reference to its use as a vanity case adapted to contain face powder or the like, together with a powder puff or similar device for applying it, and it is desirable to provide a construction that will conveniently receive the powder, holding a sufficient supply, and also maintaining the puff against movement in the receptacle. To this end, I provide a compartment in the center of the case which is preferably circular and composed in the following manner. 12 is an outer, preferably square strip abutting an intermediate correspondingly shaped strip 13, and 14 is an annular inner strip contacting with the intermediate strip 13. The several strips just referred to are provided with an overlying top portion 15, the outer edge of which conforms to the outer edge of the strip 12 while it is cut away centrally to form the circular opening 16, affording a circular compartment. The portions just referred to are bound together by means of a top covering 17 which is extended downwardly over the sides and suitably attached

by glue or other affixing medium that may also be applied between the several strips of the compartment forming means, which fits snugly within the container, as shown in Fig. 1.

I claim as my invention:

A container comprising a body, a closure upon the body consisting of a flexible covering hinged to the body and surrounding a section of material, a portion of the inner surface of which forms a mirror visible

through an aperture in said covering and a flap for securing the closure at one side of the body consisting of a reinforcing member supported by extended portions of said flexible covering folded upon each other at one edge of the closure to form a hinged connection between said closure and flap.

EDWARD N. LORSCHIEDER.
